UNITED STATES PATENT OFFICE.

BERNHARD BENEDICT, OF NEW YORK, N. Y., ASSIGNEE TO BEACON MINIATURE ELECTRIC COMPANY, OF NEW YORK, N. Y.

CIRCUIT-CLOSER.

1,107,645.

Specification of Letters Patent. Patented Aug. 18, 1914.

Application filed September 30, 1913. Serial No. 792,571.

To all whom it may concern:

Be it known that I, BERNHARD BENEDICT, citizen of the United States of America, residing at New York, in the county of New York and State of New York, have invented certain new and useful Improvements in Circuit-Closers, of which the following is a specification.

The present invention pertains to electric 10 flash light lamps, and particularly to circuit closers or switches whereby the lamp may be lighted or extinguished.

The hitherto used structures have been found objectionable because the switch after 15 a short time of use, becomes ineffective, as the parts wear off very quickly.

The object of my invention is to provide a switch that will be more durable and simpler in construction.

20 With this object in view, my invention consists in the construction, combination and arrangement of parts as hereinafter described and set forth in the claims.

To make my invention clear, I shall refer 25 to the accompanying drawing, in which similar reference characters denote corresponding parts and in which—

Figure 1 is a front elevation of my new switch as applied to the casing, which is 30 shown broken away at its ends; Fig. 2 is a longitudinal section of the complete lamp taken on line 2—2 of Fig. 1; Fig. 3 is a partial longitudinal section taken at a right angle to that of Fig. 2, the ends of the lamp 35 being broken away; Fig. 4 is an enlarged partial section similar to that of Fig. 2; and Fig. 5 is a rear view of the slide forming a part of the switch.

The lamp is composed, as usual, of a casing *a* of hard rubber or other insulating material, which is open at both ends. In one of these open ends is fastened, by the usual threaded thimble *b'*, the reflector *b* which carries the lamp (not shown), and the other 40 end through which the battery *c* is inserted, is closed by a removable cap *d*. As usual, one terminal of the lamp makes contact with one pole of the battery, while the other terminal of the lamp is electrically connected 45 to the metal reflector *b*. Inside the casing 50 two longitudinally extending metal strips *e*, *f* are provided, of which strip *f*, as usual, is in electric connection with the reflector *b* and is riveted to the casing as at *f'*, while 55 the strip *e* is electrically connected to the

other pole of the battery located at the opposite end of the latter.

Secured to the outside of the casing *a* is a box-shaped metal frame *g* in which is arranged the spring slide forming part of the 60 circuit closer or switch. Thus far the construction is well known.

My invention resides in an improvement in the circuit closer or switch whereby the latter is rendered more reliable and durable. 65

The improvement consists in that the metal strip *f* at its free end is formed to a spring hook *f'* which is adapted to project with its outwardly bulging surface into the box *g* through a narrow slot *a'* in the casing 70 *a*. The slide *h* is a flat metal piece having a rough outer surface and slidably bearing on the outer surface of the box or frame *g*. The same is provided with a neck portion *h'* that projects through a narrow slot *g'* 75 of the frame *g* and carries inside the latter a spring plate *i* suitably fastened to said neck. This spring plate at its upper end is also formed to a spring hook *i'* which with its bulging surface is directed toward the 80 casing *a* and is adapted to normally bear on the latter as at *a'*.

The metal strip *e* is conductively connected to the metal box or frame *g*, as by a rivet *e'*. When the slide *h* is moved from its 85 inoperative or circuit opening position into the circuit closing position, the spring part *i'* of the plate *i* will be brought into contact with the spring part *f'* of the metal strip *f* whereby the battery circuit will be 90 closed. Owing to the spring force of the two oppositely arranged hook-shaped parts *i'* and *f'* the latter will constantly project into one another's path and thereby insure 95 perfect contact. The principal advantage of this structure, however, is that the wear of the operating parts or the slackening of the box or frame or of any other part of the circuit closer or switch will not affect the 100 operativeness of the latter.

In order that the slide may be held in the circuit opening position when the lamp is not in use and that the life of the battery may thus be lengthened, I provide an automatically working locking means for the 105 slide.

In the present embodiment of my invention this locking means consists of a rounded projection *g'* extending from the inner 110 surface of the frame or box *g* and adapted

to engage a correspondingly shaped depression i^2 in the plate i when the slide is moved into inoperative position.

Since various modifications may be made 5 in the structure without deviating from the spirit of my invention, I do not wish to restrict myself to the details described and shown.

What I claim and desire to secure by Letters Patent is:—

1. In a circuit closer, a casing having a circumferential aperture, a conductor strip in said casing the free end of which is resilient and formed to a part bulging outwardly through said aperture and a second conductor consisting of a slidable resilient member outside of said casing and having a part bulging inwardly, the two bulging parts being adapted to constantly project into one another's path and to close the circuit when the sliding member is moved into circuit closing position.

2. In a circuit closer, a casing having a circumferential aperture, a box fastened to the exterior of said casing over said aperture, a conductor consisting of a flat slide movably guided in said box and a spring plate carried by said slide and having a part bulging toward said casing, and a sec-

ond conductor consisting of a strip having a 30 bulging part projecting through said aperture into the said box, said two spring parts being adapted to constantly project into one another's path and to come into contact with one another when the slide is moved 35 into circuit closing position.

3. In a circuit closer, a casing having a circumferential aperture, a box fastened to the exterior of said casing over said aperture, a conductor consisting of a flat slide 40 movably guided in said box and a spring plate carried by said slide and having a part bulging toward said casing, a second conductor consisting of a strip having a 45 bulging part projecting through said aperture into the said box, said two spring parts being adapted to constantly project into one another's path and to come into contact with one another when the slide is moved 50 into circuit closing position and an automatically operating locking means for said slide.

In testimony whereof I affix my signature in presence of two witnesses.

BERNHARD BENEDICT.
